ELECTRIC SYSTEM OF LIFT CONTROL

Norman Carol Smart, Binley, near Coventry,
England, assignor to The General Electric
Company Limited, London, England

Application March 30, 1935, Serial No. 13,810
In Great Britain March 26, 1934

10 Claims. (Cl. 187—29)

This invention relates to electrically controlled lifts and like limited travel mechanisms, and more especially to lifts of the variety operated by the user.

5 Lifts are known in which the operation of a push button at a particular floor by a user brings the lift to that floor, whereupon the user enters the lift and by depressing one of a number of buttons in the lift causes it to travel to the required floor. This type of system, though moderately simple, is not the simplest possible, in that the user must perform two separate operations, firstly, that of calling the lift to the floor where it is required, and secondly, that of giving an indication as to its destination when it has arrived there.

Lift controlling systems are also known in which a user, by the performance of a single operation, affects the controlling mechanism of the lift so as to bring the lift to or to stop it at the required floor and thereafter to cause it to travel to and stop at a required floor. To accomplish this, at each floor is provided a series of electromagnetically locking push buttons bearing the 20 numbers of the other floors served by the lift. A caller at one floor presses a button corresponding to the floor to which he wishes to travel, whereupon the lift is brought to or stopped at the floor where the button has been depressed, and, after the caller has entered the lift, is caused to travel to the floor required and to stop there.

25 Systems of this nature possess certain disadvantages. One of these is that locking push-buttons have not been found suitable for use on lifts liable to heavy traffic. Another is that call storage at the various floors served by a lift necessitates a larger number of wires being run in the lift shaft, and a third disadvantage resides in that if n floors are served by the lift, the number of call storage devices, i. e. electromagnetically locking push-buttons or relays, has hitherto been some multiple of n^2 . This, for a lift serving a large number of floors, renders the cost of such a scheme prohibitive.

30 According to the present invention, in a user-operated lift controlling system in which a single operation only is performed both to call the lift to the user and thereafter to direct it to the required floor, calls are registered on a group of electromagnetic storage devices, such as relays, which are $k n$ in number, where n is the number of floors served by the lift, and k is a constant. Calls to be attended to by the lift are divided 35 into three classes, "effective calls", "stored calls

up", and "stored calls down", each floor being provided with three relays, each relay representing one of the types of call defined. The depression of a button at a floor operates one relay in each of two floor groups, the relays operated being determined not only by the position of the lift relative to the floor on which the push is operated, but also by the direction in which the lift is or was previously travelling, and by the direction in which the caller wishes to travel. Thus the "effective-call" relay is operated when the lift is travelling towards or has just been travelling towards the floor where the push-button is operated, and in the direction that the user requires to travel. The "down-call storage" relay is operated when the lift is travelling or has just travelled away from the floor where the push-button is operated, and the required direction of travel of the lift is downwards, whilst the "up-call storage" relay is operated under similar conditions to the above, except that the required direction of travel is upwards. The lift travels in one direction until all effective calls in that direction are answered, whereupon stored calls for the opposite direction are transformed into "effective" calls, and the lift reverses and answers them.

35 A group of follower relays, additional to those used for storage, is provided, the relays of which operate in synchronism with the position of the lift in the shaft; these relays, in conjunction with the three relays previously mentioned as being provided at each floor, control the operation of two further relays which affect drive of the lift up or down.

40 The usual facilities as regards maintaining the lift stationary when any one of the floor gates or doors is opened, and of arresting its motion by limit switches at the end of its travel, may be provided. In addition a delay device may be fitted such that when the lift stops at a particular floor, it remains at this floor for a predetermined time although the lift doors are not opened. After this time has elapsed it becomes once more 45 free to attend to other calls. If necessary, the lift may, after further delay, be caused to run to a predetermined parking position and there stopped, provided that no effective or stored calls are made before the lift reaches the parking position. If it remains out of use for a still further period, the motor-generator set or power supply driving the lift motor may automatically be shut down or disconnected, though it is re-started or 50 reconnected on the appearance of a call.

55

In order that the invention may be clearly understood, one form of lift control in accordance therewith will now be described by way of example with reference to the accompanying drawings.

The drawings show a circuit diagram of the lift control system adapted to serve four floors, the circuit being divided into three parts, shown in Figures 1a, 1b, and 3, for convenience in representation, and Figure 2 is an explanatory diagram for use in readily tracing the relays and their respective contacts in the other figures. The location of the relays and contacts are indicated by arrows in Figure 2; an arrow pointing to the left indicates that the relay or control is to be found in line with the arrow, in Figure 1a or Figure 1b, while an arrow pointing towards the right indicates that the relay or contact is to be found in line with the arrow, in Figure 3.

As shown in Figure 1a, a lift carriage LC is suitable suspended from a cable which passes over a hoisting drum directly coupled to and driven by a lift driving motor M.

A spring actuated brake operated by an electro-magnetic brake coil BS is provided for preventing rotation of the hoisting drum when the hoisting motor is not in operation. The brake coil BS when energized, releases the brake.

Energizing circuits for the field winding of the driving motor M are completed through contacts of an up-direction relay R and a down-direction relay K.

The up-direction relay R and the down-direction relay K are prevented from operating unless a starting relay ST is operated, so that the lift does not move until this relay ST is energized. The energizing circuit of the starting relay ST comprises the gate locks VG, on the ground floor gate and V1, V2, and V3 on the first, second and third floor gates respectively, an emergency stop push button VC in the lift carriage LC and limit contacts TL and BL respectively mounted near the top and bottom of the lift shaft and operated should the lift carriage by any means over-run its normal extent of travel in the shaft.

The group of follower relays GF, 1F, 2F, and 3F is provided for the purpose of following the movement of the lift in the shaft. Follower relay GF is energized when the lift is at or near the ground floor, follower relay 1F is energized when the lift is at or near the first floor and so on.

Lift actuated position indicating contacts J1, J2, and J3 are provided in the lift shaft midway between the ground floor and the first floor, midway between the first and second floors, and midway between the second and third floors respectively. These contacts are actuated by cam operating means CJ on the lift carriage itself and serve to determine which of the follower relays GF, 1F, 2F or 3F is to be energized. These lift actuated contacts J1, J2, and J3 are operated towards the left in the drawing by the passage of the lift carriage in an upward direction and to the right as the carriage moves downwards.

A stop relay P of the well-known inductor pattern is mounted on the lift carriage and remains operated so long as the lift carriage is at or near a floor. The operation of a relay of the inductor pattern is well-known and need not be fully described herein; it should be pointed out, however, that for clarity in representation one of the four necessary inductor plates FP is shown at the stop relay P in Figure 1a of the drawings.

If desired, this stop relay P may be of the mechanically actuated type and not necessarily of the inductor pattern.

In the representation of the contacts in the diagram, it has been assumed that the lift carriage LC is standing at the ground floor having previously travelled in a downward direction, there being no outstanding unanswered calls for the lift carriage and the gates on all floors being shut.

A group of relays, such as effective call relay GE, u-call storage relay GU and down-call storage relay GD on the ground floor, is provided for each floor served by the lift carriage, the total number of such relays being $3n$ where n is the number of floors; in the present representation (n being four) there are 12 relays and connection to these relays is made by wires 1, 2, 3, and 4 which traverse the lift shaft.

It will be seen that the number of wires is equal to the number of floors served and this is a distinctly useful feature as compared with those systems in which the necessary number of such wires varies as the square of the number of floors served.

The wires 1, 2, 3, and 4 are connected to groups of non-locking, call push buttons GP, 1P, 2P, and 3P situated on the ground floor, first, second and third floors respectively. Each group consists of three buttons, such as, in the case of group GP, for example, GP1, GP2 and GP3, each of which is separately operable. If a person on the second floor wishes to travel in the lift to the ground floor he pushes call button 2PG of the group of buttons on the second floor. If he is on the first floor and wishes to travel to the top floor, he pushes call button 1P3 of the group of buttons of the first floor.

It may happen that the lift is in use when a person makes a call for the lift carriage to convey him to a particular floor, and it is to safeguard this state of affairs that the groups of three relays, as effective call relay GE, up-call storage relay GU and down-call storage relay GD for the ground floor, are provided.

It is arranged that if the lift carriage is, say, at the first floor, having previously travelled upwards, and a person presses a push button corresponding to the second or third floor (i. e. if he presses call button 1P3), then the effective-call relays 1E and 3E operate to cause the lift to move to the required floor immediately. Should the person on the first floor press the call button 1PG, indicating that he wishes to be carried to the ground floor then, since the lift carriage has been travelling upwards, the down-call storage relays 1D and GD operate, the lift meanwhile answering any up-calls that may have been made.

Similarly if the lift carriage has been travelling downwards and an up-call is made, say, at the second floor for the third floor, the up-call storage relays 2U and 3U are operated.

Stored calls are answered when there are no more "opposite-direction" calls to be answered.

The call button groups, such as GP, and the effective-call and storage relays employ three separate batteries, the terminals of which are connected to the points marked +U -U, +E -E, and +D -D, (see lower left Fig. 3 and at respective relays Fig. 1b), these batteries being used for up-call storage, effective call, and down-call storage signals respectively.

The stored signals are converted automatically in this system to effective call signals in their

correct order, the lift being adapted, however, to answer all calls involving travel in a single direction, before reversing and travelling to answer any calls which may be stored necessitating travel

5 in the opposite direction, as will be shown later.

Slow acting up and down travel relays UR and DR for completing energizing circuits of the up-direction relay R and down-direction relay K respectively, are adapted to be actuated, through

10 resistances YD, YE respectively, when the effective-call actuated relay EC is energized. The energizing circuit of the effective-call-actuated relay EC includes the call-responsive relay C which controls the operation of another slow act-

15 ing, transfer relay T which, in turn, controls the operation of still other slow-acting up and down storage-circuit-holding relays CU and CD. The function of the storage-circuit-holding relays CU and CD is to control holding circuits for the

20 up-call storage relays GU, 1U, 2U, 3U and for the down-call storage relays GD, 1D, 2D, 3D, respectively.

In order that the operation of the lift system may be fully understood it is now proposed to 25 outline the different sequences of actuation of the relays when the lift carriage answers some specimen calls.

It should be borne in mind that the drawings show the positions of the relay contacts when, as 30 has been mentioned above, the lift carriage is standing at the ground floor with no stored calls and with the lift gates all shut, the lift having previously been travelling in a downward direction.

35 Assume that a call is made at floor 1 for the carriage to travel to floor 3. The call is sent by momentarily depressing call push 1P3. The following operating sequence now takes place:—

Up-call storage relay 1U is operated over the 40 path —U, coil of relay 1U, lead 2, centre contact of call button 1P3, contacts 2/3, 3/3 and b4 to +U through resistance YA.

Similarly up-call storage relay 3U is operated over the path —U, coil of the relay 3U, lead 4, 45 lowest contact of call button 1P3, contacts 2/3, 3/3 and b4 to +U through resistance YA.

Contacts of up-call storage relay 1U actuate as follows:—

1u1 locks the relay 1U operated over lead 6 50 in series with up-call signal relay US and call responsive relay C through contact cu1; relays US and C operate.

1u2 prepares a holding circuit for effective-call relay 1E.

55 1u3 opens a short circuit applied to up-travel relay UR from positive on contact g1 through contacts ge3, gu3, gd3, 1d3, 1e3, 1e4, 1u3, 2d3, 2e3, 2e4, 2u3, 3u3, 3d3, 3e3. Up-call signal relay US operates contact us1 and removes a positive potential from the opposite side of up travel relay UR at the same time contact 1u3 opens the short circuit and so prevents operation at this time, but an operating positive potential is shortly to be applied to the opposite side of up travel relay 65 UR by contact ec2.

1u4 prepares an energizing circuit for retardation relay G. Contacts of up-call storage relay 3U actuate as follows:

70 3u1 locks the relay 3U operated in series with up-call signal relay US and call responsive relay C.

3u2 prepares a holding circuit for effective-call relay 3E.

75 3u3 further opens the path short-circuiting up-travel relay UR as above described.

The contact c1 of call responsive relay C actuates to operate call transfer relay T.

Contacts of call transfer relay T actuates as follows:

t1 operates the effective call relay 1E through contact b1, lead 8, and contact 1u2 and operates effective call relay 3E through contact b1, lead 8 and contact 3u2.

t2 operates up-storage circuit-holding relay CU through contact b2.

t3 prevents operation of direction setting relay B when up-travel relay UR is operated later.

Contact cu1 of up-storage circuit-holding relay CU cuts the holding circuits of up-call storage relays 1U and 3U at contacts 1u1 and 3u1; these 15 relays thereupon release as does up-call signal relay US.

By these operations, the call registered through up-call storage relays 1U and 3U in the first place as a stored-up call, since the previous movement 20 of the lift carriage had been away from the call, is transferred into an effective call, i. e. one to which the lift carriage may respond immediately. The sequence of operations causing response of the lift carriage to a now effective call from floor 25 1 for the lift to travel from that floor to floor 3 is as follows:—

Effective call relays 1E and 3E have now been operated and their respective contacts actuate as follows:—

30 1e1 completes a holding circuit for the effective call relay 1E through lead 9 and effective call-actuated relay EC and call responsive relay C to the positive terminal of a battery.

1e2 prepares an operating circuit for retardation relay G.

1e3 and 1e4 break further the path short-circuiting the up-travel relay UR.

3e1 duplicates the actuation of 1e1, but the holding circuit is for the effective call relay 3E. 40

3e2 prepares an operating circuit for retardation relay G.

3e3 breaks still further the path short-circuiting the up-travel relay UR.

The effective-call-actuated relay EC is operated by closure of contacts 1e1 and 3e1.

ec1 breaks a possible operating circuit for retardation relay G.

ec2 operates up-travel relay UR by connecting one side thereof to the positive terminal of the 50 battery.

ec3 actuates for possible operation of down-travel relay DR.

The up-travel relay UR is operated and its contacts actuate as follows:—

ur1 opening prevents false operation of down-travel relay DR.

ur2 de-energizes call transfer relay T, which being lagged, releases slowly.

ur3 prepares an operating circuit for direction- 60 cutting relay B.

ur4 energizes the up-direction relay R and the brake coil BS in series over the path contact k1, coil of R, contacts st2 (operated) and nr1 and brake coil BS to the negative terminal of the 65 battery.

The brake is removed from the motor shaft at the same time as the up-direction relay R is operated.

Contacts of the call transfer relay T (de-energized) actuate in the following manner:—

t1 breaks the call transferring circuit through contact b1.

t2 releases the up-storage-circuit-holding relay CU.

t3 operates direction setting relay B, through contact ur3, to a position corresponding to an upward travel of the lift carriage.

Direction-setting relay B is of the two-position type for example as shown in British patent specification, No. 354,847, and its contacts actuate thus:—

b1 changes the call transferring circuit so as to be ready to deal with future registered down-10 calls.

b2 changes over from up-storage-circuit-holding relay CU to down-storage-circuit-holding relay CD.

b3 changes from paths linked with contacts 15 gu4, tu4 and 2u4 to paths linked with contacts 1d4, 2d4 and 3d4.

b4 and b5 change over the battery connections to the call button groups GP and 3P to effect appropriate call storage conditions, but no 20 further relays are operated even though the call button FP3 is still depressed.

Actuation of the contacts of the up-direction relay R is:—

r1 prevents simultaneous operation of the 25 down-direction relay K.

r2 locks the up-direction relay R operated (it is released later, as will be shown, by operation of braking relay NR).

r3 and r4 energize the lift motor M so as to 30 drive the lift carriage LC upwards.

The lift carriage now travels upwards and, if desired, automatic accelerating devices, not shown, may be employed, in order to produce a steady rate of increase of acceleration. Such devices are well-known and need not be further discussed here.

Then mid-way between the ground floor and the first floor, the cam CJ1 on the lift carriage LC operates contact J1 to the left in the drawing, 40 thereby releasing the follower relay GF and energizing the follower relay IF.

if1 transfers the point at which the short-circuiting path was applied to the up-travel relay UR to another point in the contact chain ge3 to 45 3e3. The short-circuit previously provided by positive at contact g1 is removed by release of the follower relay GF.

if2 and if3 actuate to prepare the call button 50 circuits for possible actuation of contacts b5 and b4 to +E.

if4 de-energizes effective-call relay 3E which releases.

if5 operates retardation relay G through contact 1e2; the retardation relay G locks operated 55 through contact g1 to contact nr2, meanwhile contact g2 operates halt relay H.

if6 and if7 serve no particular purpose in the operation immediately under consideration. The contacts of the halt relay H actuate as follows:

60 h1 prepares to lock the halt relay H operated while a lift gate at any floor is opened, or until after the lapse of a predetermined time (as will be described later).

h2 prepares an operating circuit for the braking relay NR. The lift carriage now approaches the first floor from which the call was made. When near the floor, the stop relay P is operated and its contact p1 causes operation of the braking relay NR. The stop relay P remains operated 70 as long as the lift carriage is near or standing at the floor.

nr1 de-energizes the brake coil BS. This re-applies the brake to the motor driving shaft, causing slowing down and eventual stoppage at the first 75 floor. At the same time this contact nr1 de-en-

ergizes the up-direction relay R causing de-energization of the motor M.

nr2 releases the retardation relay G.

The would-be passenger opens the lift gate at the first floor opening gate lock contact VI as he 5 does so. This releases the starting relay ST.

st1 holds the halt relay H operated while the gate is opened.

st2 opens the circuit of the up-direction relay R, the down-direction relay K and the brake coil 10 BS, so that no movement of the lift carriage can take place whilst the gate is open.

Having entered the lift carriage LC, the passenger closes the gate once more; the starting relay ST is reoperated. 15

st1 releases halt relay H.

st2 recloses the up-direction relay R circuit and the brake coil BS circuit.

The braking relay NR is once more released through breaking of contact h2 so that the up-direction relay R and the brake coil BS are re-energized in series to positive on contact ur4; the up-travel relay UR is still energized to negative battery through the resistance YD as, although the point of application of positive potential to the contact chain 3e3 to ge3 has been moved from g1 to if1, effective-call relay 3E is maintained operated and its contact 3e3, being open, prevents the up-travel relay UR from being short-circuited by this contact path. 30

The lift now travels in an upward direction releasing the stop relay P and in turn operating the follower relays 2F and 3F through cams CJ2 and CJ3 cooperating with the contacts J2 and J3 respectively. 35

Operation of follower relay 2F effects no control of the lift as the relays are set for travel to the third floor only.

When the follower relay 3F operates its contacts actuate in the following manner:—

3f1 transfers the point at which the short-circuiting path was applied to the up-travel relay UR to the end of the contact chain 3e3 to ge3, thereby short-circuiting the up-travel relay UR; the short-circuit previously provided by positive at contact if1 is removed by release of the follower relay IF. 45

3f2 and 3f3 prepare the call button circuits for possible actuation of contacts b5 and b4 to +E through resistance YC. 50

3f4 de-energizes effective-call relay 3E which releases.

3f5 operates the retardation relay G through contact 3e2; the retardation relay G locks operated through contact g1 to contact nr2, contact 55 g2 meanwhile re-operating halt relay H.

3f6 prepares another operating circuit for retardation relay G.

Halt relay H operates as before and its contact h2 prepares an operating circuit for the braking relay NR which is operated as above described when the lift carriage approaches the floor where inductor plate FP3 operates stop relay P. 60

The contacts of braking relay NR perform functions already described and the lift carriage 65 is brought to rest at the third floor as required.

Effective call relay 3E being released, as above stated, this clears the system of all unanswered calls and release of starting relay ST, halt relay H and braking relay NR by the opening and closing 70 of the lift gate on the third floor renders the system capable of dealing with further calls.

As already stated the lift carriage is adapted to answer all calls involving travel in a single direction before reversing and travelling to an- 75

swer any calls which may be stored necessitating travel in the opposite direction. Thus when the lift carriage is at floor 3, a call is made necessitating travel from floor 2 to the ground floor, 5 and whilst the lift carriage is travelling towards floor 2 another call is made from floor 1 to floor 3, the lift carriage answers the two calls in the order in which they are made. This is performed as follows:

- 10 The first call is made by depressing call button 2PG. Down-call storage relays 2D and GD are thereupon operated. The circuits for these relays 2D and GD are from +D resistance YB contacts 55, gf2 (now closed), 1f2 call button 2P1 to the relay coils and thence to -D. When operated 15 the two relays lock through contacts 2d1 and gd1 respectively over lead 5 in series with down-call signal relay DS and call responsive relay C both of which operate.
- 20 The short-circuit applied to down-travel relay DR by a positive potential at 3f1 is removed by actuation of relay contacts 2d3 and gd3, with the result that the down-travel relay DR is operated when contact ec3 actuates later; the sequence 25 of operations involving the operation of the effective-call-actuated relay EC need not be repeated here as it is similar to the sequence detailed above.
- Previous to the operation of the down-travel 30 relay DR the call, registered as down-call on down-call storage relays 2D and GE, is changed to an effective-call and the registration is transferred to the effective-call relays 2E and GE as follows:—
- 35 When call responsive relay C operates, its contact c1 operates call transfer relay T.
- t1 applies positive potential through contact b1 (now in a right hand position), lead 7 and contacts 2d2 and ge2 to effective-call relays 2E and 40 GE which thereupon operate.
- t2 energizes down-storage-circuit-holding relay CD.
- t3 prevents direction setting relay B from changing over.
- 45 The contact cd1 of down-storage-circuit-holding relay CD releases the down-call storage relays 2D and GD, though only after contacts of these relays have operated the effective-call relays 2E and GE as above described.
- 50 The call transferring operation is thus effected, the call now being an effective call.
- Operation of the effective-call relays 2E and GE causes actuation of the effective-call-actuated relay EC in series through contacts 2e1 and ge1.
- 55 The effective-call-actuated relay EC actuates as follows:
- ec1 breaks a possible operating circuit for the retardation relay G,
- ec2 actuates for possible operation of up-travel 60 relay UR.
- ec3 operates the down-travel relay DR by connecting one side thereof to the positive terminal of the battery.
- 65 Operation of the down-travel relay DR initiates downward travel of the lift carriage, this travel being performed in a similar manner to that already described in connection with upward travel, except of course that the down-direction relay K is this time operated—through actuation of contact dr4—and, through its contacts k3 and k4, starts up the motor M in the reverse direction.
- 70 dr3 closes an operating circuit for the direction setting relay B which is once more moved to the 75 position shown in the drawing.

dr2 opens the operating circuit of call transfer relay T.

dr1 prevents false operation of the up-travel relay UR.

The contacts of the call transfer relay T actuate to perform the following operations:—

t1 opens the call transferring circuit through contact b1.

t2 de-energizes the down-storage-circuit-holding relay CD thus enabling further down calls to 10 be stored.

t3 completes the operating circuit for the direction setting relay B through the contact dr3.

The lift now travels to floor 2 and stops in a manner similar to that already described, entry 15 of the passenger and reclosing of the lift gates causing the lift carriage to restart in a downward direction towards the ground floor.

A call is made from floor 1 to floor 3 by the depression of call button 1P3; a circuit is thereupon completed from +U through resistance YA, contacts gf3 (closed) and 1f3, call button 1P3, leads 2 and 4 and coils of the up-call storage relays 3U and 1U to -U, and these two relays operate. As the call transfer relay T is at present 25 de-energized by contact dr2, the contacts 1u2 and 3u2 cannot operate the effective-call relays 1E and 3E, i. e. the second call cannot be transferred into an effective one, until the down-travel relay DR is released once more when the lift 30 carriage reaches the ground floor, where it is brought to rest by actuation of the retardation relay G through contacts gf5 and ed2.

As the lift carriage cam CJ1 actuates contact J1 midway between the first and the ground 35 floors, the follower relay GF is operated and follower relay 1F is released, this transferring a positive potential from 1f1 to gf1 and short-circuiting down-travel relay DR which releases slowly.

dr1 closes, there being no need to safeguard 40 false operation of up-travel relay UR.

dr2 energizes call transfer relay T (call responsive relay C being operated in series with up-call signal relay US due to the registered up-call from floor 1 to floor 3).

dr3 further opens the operating circuit for direction setting relay B.

dr4 slowly opens the circuit of the down-direction relay K.

t1 operates effective-call relays 1E and 3E 50 through contacts b1 (in position shown) and 1u2 and 3u2 respectively.

t2 energizes the up-storage-circuit-holding relay CU which cancels the stored upcall by releasing up-call storage relays 1U and 3U at its contact cu1.

The operation of the lift carriage is not yet affected by this transference as the down-direction relay K is locked operated through contact nr1, which will be opened only when the carriage reaches the ground floor. When the down-traveling passenger reaches the ground floor and has opened the lift gates and the retardation relay G, halt relay H and braking relay NR have been released, closure of the lift gates enables up-travel relay UR, which is operated by the opening of contacts 1e3 and 3e3, to operate the up-direction relay R and the lift carriage travels to the first floor. Here the carriage stops in the manner already described, picks up the waiting caller, 70 restarts upwards and travels to the third floor.

Now a third example of the operation of the lift system is that in which calls are made simultaneously from, for example, the ground floor to the second floor and from the first floor to the 75

third floor. The lift will be considered as being again at the ground floor so that the relays and contactors are in the positions shown in the drawing.

5 In this example, the call-buttons GP2 and 1P3 are depressed GP2 being assumed to be depressed a few seconds prior to 1P3.

Up-call storage relays GU and 2U are initially operated over the path +U, resistance YA, contacts b4, 3/3, 2/3, and 1/3, call button GP2, the relay coils and -U. This call is transferred into an effective call immediately since the operation of call responsive relay C in series with the up-call signal relay US, as will be clear from the 10 preceding description, completes at its contacts c1 the operation circuit for the call transfer relay T, so that the lift carriage commences to travel upwards. Meanwhile the call button 1P3 has been depressed (actually for the following sequence of operations to take effect, it must be 15 depressed before the lift carriage cam CJ1 has operated contact J1) and effective-call relays 1E and 3E are operated over the path +E, resistance YC, contacts b4 (now operated to right hand position), 3/3, 2/3, call button 1P3 to -E through the operating coils of the relays. Then, although the lift carriage was originally going to travel to the second floor before stopping, it now stops at the first floor on the way as its movement is arrested by the operation of the retardation relay G from contacts 1/5 and 1e2. When the second passenger has entered the carriage and has closed the gates, the carriage re-starts upwards, 20 stops at floor 2, re-starts a second time and finally comes to rest at the third floor, whence it travels to answer any other calls that may have been made. The detailed operation of the system to bring about the restarting and subsequent movement of the lift carriage will be clear from 25 the previous description of similar operations and will not be explained here.

Now it may happen that the lift carriage is standing at the ground floor and call is made for the carriage to convey a passenger from the second floor to the first. It is obvious that the call is un-convertible into an effective call immediately as to answer the call, the carriage must travel to the second floor and then reverse its direction of travel. It will be as well therefore 30 to point out the sequence of operations performed by the system in answering such a call. These are as follows:-

When the call is made, the depression of the appropriate call button 2P1 causes operation of the 35 down-call storage relays 2D and 1D over the path +D, resistance YB, contacts 3/2, 2/2, call button 2P1 to -D through the coils of the down-call storage relays 2D and 1D. Down-call signal relay DS and call responsive relay C are operated 40 at the same time as the down-call storage relays 2D and 1D.

c1 operates the call transfer relay T, but, as the contacts of direction-cutting relay B are actuated to the positions corresponding to the 45 transference of stored up-calls only, no transference takes place.

As however down-call storage relay 2D is operated, its contact 2d3 removes the short circuit from the up-travel relay UR which operates to 50 positive at contact d1 (operated) through contact d1 to negative through resistance YD. Operation of the up-travel relay UR initiates upward travel of the lift carriage in the manner already clearly outlined until the lift carriage cam 55 CJ2 moves contact J2 over and consequently ac-

tuates the follower relay 2F. A circuit is thereupon completed from positive at contact 2f1, through contacts 2d4, 3d4, b3 and ec1 to negative through the coil of retardation relay G which is therefore actuated and then locks through its contact g1. When the call transfer relay T was released on the operation of up-travel relay UR the direction setting relay B and consequently the contact b3 was operated to a position to effect transfer of stored down-calls. 10

Then the lift carriage stops at the second floor and the passenger enters and closes the lift gates, the stored down-call is transferred from down-call storage relays 2D and 1D to effective-call relays 2E and 1E, the call thereby becoming effective. Travel of the lift carriage in a downward direction then follows, the carriage stopping at floor 1 to enable the passenger to alight. Closure of the gates once more renders the system ready to answer calls in or for either di- 15 20

Further facilities afforded by the lift system according to the invention are of known type. For example, should the lift carriage by any means over-run its normal extent of travel, the 25 limit contact TL or BL is operated at the top or bottom of the shaft thereby releasing starting relay ST, the contact s1/2 of which de-energizes whichever up or down direction relay R or K is 30 energized and applies the brake by de-energization of the brake coil BS. In addition a delay device (not shown) connected to lead 10 (Figure 3) can be provided in order to ensure that the lift carriage stops sufficiently long at the floor 35 in order to enable the passenger to enter or leave the lift carriage without its being started away from the floor before the gate can be opened. This delay circuit can be of any known type such as that afforded by a thermostat or dashpot the 40 action of which is initiated each time the lift carriage stops at a floor. The action of the thermostat or other delay consists of applying a holding potential to lead 10 for a period of, for example, 5 seconds, this preventing the release of halt relay H and consequently holding braking 45 relay BR operated, contact nr1 of which prevents operation of either of the up or down direction relays R or K. This facility may be combined with another, that of causing the lift to drive to a predetermined parking position if the 50 lift remains unused after a further predetermined time—say one minute. A circuit whereby this may be effected is shown in application Serial No. 12,332, in which a neon tube relaxation 55 discharge circuit is shown as stepping a switch which provides various time delays, although the invention does not necessarily involve the use of this particular circuit. The circuit shown in the aforementioned application also provides means whereby the power supply to the lift driving motor 60 may be removed at the end of a still further time delay, this being useful when the lift motor is driven from a Ward-Leonard motor generator set, in which case, when the lift is out of use, it is economical to shut down not only the lift driving motor, but also the motor generator. If the lift carriage has been moved to a parking position, or if the motor generator set has been 65 shut down, and a call appears, the delay circuit is reset, the motor generator re-started, and the 70 whole cycle is ready to be recommenced after the call has been answered.

I claim:

1. A push button operated automatic lift controlling system comprising a group of floor call 75

- buttons at each floor, a group of three relays for each floor including up and down call-storage relays and an effective-call relay, independent circuits for operating said relays by operating 5 floor call buttons, a transfer relay for transferring calls from call-storage relays to effective-call relays, a relay arranged to be operated by call-storage relays for effecting operation of said transfer relay and relay circuits controlled by the 10 effective-call relay for operating the lift in response to the floor button depressed.
2. A push button operated automatic lift controlling system as in claim 1 wherein relays controlled by said effective-call relays and the respective up and down call-storage relays are provided for determining the direction of motion of the lift and for stopping it at the required floors. 15
3. A push button operated automatic lift controlling system comprising a group of relays for each floor including up and down call-storage relays and an effective-call relay, circuits for operating said relays, a group of floor call buttons at each floor for closing the respective circuits for operating said relays according to the calling 20 floor and the destination, relays arranged to operate in series with the respective call-storage relays for determining the direction of travel of the lift, a transfer relay for effecting operation of the corresponding effective-call relays for transferring calls thereto from the operated call-storage 25 relays, a relay operated in circuit with the effective-call relays for controlling circuits for effecting operation of the lift in a direction responsive to call buttons operated.
- 35 4. A push button operated automatic lift controlling system as in claim 3 wherein relays including a double-throw relay arranged to be controlled by said effective-call relays and the transfer relay are provided for determining the direction of motion of the lift.
5. A push button operated automatic lift controlling system as in claim 3, wherein follower relays arranged to be actuated by the lift in passing from floor to floor are provided for controlling the circuits of said call-storage relays and for effecting operation of other relays for stopping the lift according to floor call buttons operated. 40
6. A push button operated automatic lift controlling system comprising a group of floor call buttons at each floor, means including an up call-storage relay for each floor, means including a down call-storage relay for each floor, independent circuits for said up call and down call relays respectively, the respective call buttons at each 45 floor being arranged for operating at least two of said call-storage relays, one for the calling floor and one for the floor called, a transfer relay controlled by said call-storage relays, means including an effective call relay for each floor arranged to be operated by said transfer relay, for effecting operation of the lift in the direction required by the call, follower relays arranged to be operated by the lift as it passes from floor to floor and relays and circuits controlled by said follower re- 50
- lays in cooperation with said effective-call relays for determining the direction and extent of travel of the lift.
7. A push button operated automatic lift controlling system comprising an up call-storage 5 relay, a down call-storage relay and an effective-call relay for each floor, a group of floor call buttons at each floor for calling each of the other floors, independent current sources for operating the respective relays, two circuits from each of 10 said call-buttons for simultaneously operating two corresponding relays, one for the calling floor and one for the floor called, direction determining relays arranged to be operated by the up and down call-storage relays, a transfer relay arranged to be operated by the call-storage relays for transferring calls by operating the two effective-call relays corresponding to the two call-storage relays, operated by the call button, and relays and circuits controlled by the effective-call 15 relays for stopping the car at the calling and called floors. 20
8. A push button operated automatic lift controlling system as in claim 7, wherein a relay arranged to be operated in series with operated effective-call relays cooperates with follower relays operated by the lift in passing from floor to floor for controlling the stopping of the car successively at the calling and called floors as indicated by the operated call-storage relays. 25
9. A push button operated automatic lift controlling system as in claim 7 wherein a starting relay operated by up and down limit switches and by the opening and closing of gates at the respective floors is arranged to control operation of the lift motor and follower relays operated by the lift in passing from floor to floor cooperate with operated effective-call relays for stopping the lift at the calling floor and opening and closing of the gate at that floor by operating said starting relay 30 permits immediate restarting of the lift toward the called floor when the gate is closed. 35
10. A push button operated automatic lift controlling system comprising call-storage relays for up and down calls and an effective-call relay for each floor, a group of floor call buttons at each floor, each call button being arranged to close circuit for operating at least two corresponding relays, one for the calling floor and one for the floor called, independent current sources for operating the respective call-storage and effective-call relays, a plurality of contactors for determining which of said current sources is utilized when a call button is operated and relays arranged to be operated according to the direction 45 of movement and position of the lift and which call-storage and effective-call relays are operated for positioning said contactor, the arrangement being such that if call buttons are operated on two different floors which may be served in succession, the effective-call relays are operated directly by the push buttons from one of said independent current sources. 50
